UNITED STATES PATENT OFFICE.

BERNARD HOLZ, OF CLEVELAND, OHIO.

DESIGN FOR AN ELECTROLIER.

Application filed March 20, 1925. Serial No. 12,776. Term of patent 3½ years.

To all whom it may concern:

Be it known that I, BERNARD HOLZ, a citizen of the United States, residing at Cleveland, county of Cuyahoga, and State of Ohio, have invented a new, original, and ornamental Design for an Electrolier, of which the following is a specification, reference being had to the accompanying drawing, forming part thereof.

In the figures, Fig. 1 is a side elevation of the electrolier and Fig. 2 is a plan thereof.

I claim—

The ornamental design for an electrolier as shown.

BERNARD HOLZ.
